United States Patent Office

Des. 203,659
Patented Feb. 8, 1966

203,659

CLEAT CLEANER

Jack Pleasants, Somerville, N.J., assignor to Nova Products, Inc., Springfield, N.J., a corporation of New Jersey

Filed Apr. 15, 1965, Ser. No. 84,798

Term of patent 14 years

(Cl. D9—2)

FIG. 1 is a perspective view of a cleat cleaner, showing my new design;

FIG. 2 is a side elevational view thereof; and

FIG. 3 is a bottom view thereof.

I claim:

The ornamental design for a cleat cleaner, substantially as shown.
